FIGURE TOY AND METHOD OF MAKING
THE SAMEMario Caruso, Maplewood, N. J., assignor to The
Lionel Corporation, New York, N. Y., a corpora-
tion of New York

Application July 8, 1944, Serial No. 544,064

3 Claims. (Cl. 46—147)

The present invention relates to figure toys and methods of making the same.

It is customary to make figure toys out of wood, but in these toys the positioning of the legs of the animal or bird has usually been a position dictated by ease of manufacturing without simulating the leg positions for locomotion of the animal or bird being simulated.

According to the present invention the figures employed on the toys are designed to have the legs in front of or behind one another somewhat as appears in the animal or bird when in motion. These figures are preferably made out of flat blocks of wood of a thickness to provide sufficient width so that when the figure is finished the three dimensional proportions of the figure will be substantially life-like.

As these toy figures will have either two or four legs it has been found that a very convenient simple way of manufacturing such figures is to run a sawcut through the wooden block so as to separate the material which is later to form the legs on the right hand side of the block from the legs on the left hand side of the block. This sawcut preferably runs lengthwise of the block along one edge and is equidistant from the two faces of the block. The main outline of the figure can then be completed by jigsawing or routing operations while the leg outlines are formed by routing operations.

While the toy figures are susceptible of use as ornaments or as simple figure toys, it is contemplated that they will be used on wheeled toys. One preferred form of such wheeled toy has a rocker provided with small centrally disposed wheels so that the toy can readily be dragged along on these wheels, and the toy is so arranged that it tends to tilt either one way or the other about these wheels as a support so that it rides along on the wheels and one or the other surfaces of the rocker in front of or behind the wheels.

The accompanying drawings show, for purposes of illustrating the present invention, two embodiments in which the invention may take form, it being understood that the drawings are illustrative of the invention rather than limiting the same.

In these drawings:

Figure 1 is a perspective view of a block of wood showing a longitudinal sawcut;

Figure 2 illustrates a preliminary cut on one side of the block by a routing tool to form one portion of the leg;

Figure 3 illustrates the completion of the two

legs on the front side of the block by means of a routing tool;

Figure 4 illustrates the formation of all four legs by means of a routing tool;

Figure 5 illustrates the completed figure on a rocker;

Figure 6 is a fragmentary sectional view illustrating the securing of the figure to the rocker;

Figure 7 is a diagrammatic view illustrating a slightly modified method of manufacture; and

Figure 8 is a side elevational view of a rocker toy showing in heavy full lines the balanced position of the figure and rocker, showing in light full lines the position when tilted forward and in light dotted lines the position when tilted rearwardly.

In making up the figure toy a rectangular block of wood 10 illustrated in Figure 1 is provided with a sawcut 11 running lengthwise of the block. This sawcut provides two bifurcations 12 and 13 from each of which one or two legs of the figure are to be formed.

Figure 2 illustrates the use of a router 14 cutting a curved line 15 which forms one side of one of the legs. This router removes the material from the near face of the block into the sawcut.

Figure 3 illustrates additional outlines 16 to 19, inclusive, by which the remainder of the legs and belly contour of the animal are formed.

In Figure 4 the block of wood has been turned around so that the legs 20 and 21 are on the rear side, and the contour followed by the router around the front side of the block similarly provides additional legs 22 and 23. Either before or after the legs have been cut to shape with the router the remainder of block has been formed to shape either by jigsaw, router or other suitable tool so as to be completed somewhat as shown in Figures 5 and 8.

If desired, one can cut the figure toy to form shown in full lines 24 in Figure 7 by a jigsaw. The sawcut can be made before or after the jigsawing operation, then the routing tool can be on one side of the wooden block to cut along the dotted lines 25, 25 to form the near legs, and along the dot-and-dash lines 26 and 27 to form the legs on the farther side. It will, of course, be understood that further finishing operations may be applied to get rid of square corners, provide suitable roundness to the figure and carry leg outlines above the sawcut.

The completed toy illustrated in Figures 5 and 8 employs in addition to the figure 30 or 30' a rocker 31 also made of wood. The figure is secured to the rocker by screws such as indicated

at 32 in Figure 6. The rocker has a central hole 37 for an axle 38 on which is mounted two rollers or wheels 39. The body of the roller is cut back as indicated at 40 to accommodate these wheels and protect them against injury as the toy is being dragged along, and the wheels extend below the rocker as indicated.

The parts are preferably proportioned so that the center of gravity of the combined rocker and figure is in a vertical line such as indicated at 42, Figure 8, extending directly upward from the bottom of the wheels and when in this position the toy is in unstable equilibrium on the rocker. It, of course, will not stay in this position and will tilt or rock forward or back until the bottom surface 43 of the rocker engages a supporting surface such as 44. The point of contact is approximately at the point marked 45 in Figure 8, and the center of gravity has moved from the position along the vertical line 42 to a position along the sloping line 42'. This position of the parts is illustrated in light full lines in Figure 8. Should the toy tip backward the center of gravity will move to be somewhere in the line 42'' and the point of contact between the rocker and supporting surface will be at some point such as 45''. When the toy is pulled along by a string it will ordinarily drag along in the dotted line position, but as soon as the toy comes to rest the mass of material high above the center of gravity will cause it to rock from the dotted line position over to the light full line position and possibly beyond, but in all cases, unless the toy is upset, it will come to rest on either the light full line or dotted line position shown in the drawing. As the pull on the string by which the toy is being dragged along varies the toy rocks back and forth riding first nose up and then nose down.

Since it is obvious that the invention may be embodied in other forms and constructions within the scope of the claims, I wish it to be under-

stood that the particular forms shown are but a few of these forms, and various modifications and changes being possible, I do not otherwise limit myself in any way with respect thereto.

5. What is claimed is:

1. A wheeled toy adapted for use on a substantially horizontal surface comprising a rocker, a pair of wheels at substantially the center of the rocker, and a figure supported on top of the rocker, the center of gravity of the toy being a substantial distance above and directly over the axis of the wheels when the toy is balanced on the wheels, the toy tending to rock forwardly or rearwardly when out of balance and to come to rest supported by the wheels and a portion of the rocker surface in engagement with the horizontal surface, the extent that the wheels protrude being such that said engaging portions of the rocker surface are spaced substantially from the ends of the rocker so that the toy may rock farther without overturning.

2. A wheeled toy having a rocker of arc shaped configuration longitudinally and with its side walls at the center notched, and wheel carried in the notches, and horizontal axles on which the wheels are rotatably carried, the wheels extending below the rocker surface to bear on a support, lines of tangency from the lower wheel surface to the rocker surface contacting the rocker surface substantially midway between the wheel and the ends of the rocker.

3. A wheeled toy having a rocker of arc shaped configuration and a pair of centrally disposed wheels protruding a slight distance below the bottom of the rocker, the rocker carrying a figure above it, the combined rocker and figure being of unstable equilibrium when supported on the wheels alone, and rocking one way or the other about the wheels as pivots to bring the rocker against a supporting surface to one side or the other of the wheels.

MARIO CARUSO.
